[57] CLAIM

The ornamental design for a combined housing for electrical cable to power source connector and protective cable cover, substantially as shown and described.

DESCRIPTION

FIG. 1 is a front, top perspective view of the combined housing for electrical cable to power source connector and protective cable cover showing my new design; FIG. 2 is a top plan view thereof on an enlarged scale; FIG. 3 is a side elevational view thereof on an enlarged scale;

FIG. 4 is a front elevational view thereof on an enlarged scale;

FIG. 5 is a bottom plan view on an enlarged scale;

FIG. 6 is a rear elevational view thereof on an enlarged scale.

*Fig. 1.**Fig. 2.**Fig. 3.**Fig. 4.**Fig. 5.**Fig. 6.*
